United States Patent Office

Des. 233,978
Patented Dec. 24, 1974

233,978

TAG HOLDER

Donald M. Palmer, 2627 SE. 68th Ave.,
Portland, Oreg. 97206

Original design application May 17, 1971, Ser. No.
144,395, now Patent No. 227,194. Divided and this application Apr. 16, 1973, Ser. No. 351,499

Term of patent 14 years

Int. Cl. D8—08
U.S. Cl. D8—243

FIG. 1

FIG. 2

FIG. 1 is a perspective view of a tag holder showing my new design; and

FIG. 2 is a perspective view of a modified form of the tag holder shown in FIG. 1.

The present application is a division of application Ser. No. 144,395, filed May 17, 1971, now Design Pat. No. D. 227,194, issued June 5, 1973.

I claim:

The ornamental design for a tag holder, as shown and described.
